WASHING MACHINE

Wallace J. Witwer and Albert C. Bunyan, Cleveland, Ohio, assignors to The B. W. B. Company, Cleveland, Ohio, a corporation of Ohio

Application March 5, 1937, Serial No. 129,238

10 Claims. (Cl. 68—190)

This invention relates to washing machines and more particularly to devices of this character in which the washing liquid is agitated and given a turbulent motion to cleanse articles immersed 5 in the liquid.

The usual practice by which articles are washed in accordance with former methods involves the use of an agitator which is physically immersed in the liquid and actuated in a circulatory or reciprocating movement. This method is considered disadvantageous in that the agitator itself is usually in physical contact with the articles being washed so that they are often jerked and injured, such as by tearing or breaking.

15 In some constructions the agitator is in the form of a receptacle or basket in which the articles to be washed are placed. In the washing operation the entire basket, including the articles, are agitated within the washing liquid, causing 20 the liquid to eddy and flow over the articles. Another method of washing is by pumping the washing liquid through a plurality of jets or nozzles which cause the liquid to impinge upon the articles being washed.

25 None of these methods has been accepted as a completely satisfactory washing system. A disadvantage common to all of the methods is that a more or less elaborate machine is necessary so that the cost of manufacture is relatively high, 30 and, accordingly, washing machines are not in as common use as would be the case if the cost of manufacture could be reduced.

It is, therefore, an object of the present invention to provide a washing machine which is 35 simple in design and inexpensive to manufacture and one which will be economical to operate.

40 Another object is to provide a washing machine in which the washing liquid may be churned or agitated without the agitating means coming into frictional engagement with the articles being washed.

Another object is to provide a washing machine in which the articles to be washed may be immersed within the washing liquid while the liquid 45 is caused to alternately flow through or over the articles in opposite directions.

A further object is to provide a washing machine in which the washing chamber is relatively free from obstructions and recesses, so that there 50 will be a minimum opportunity for articles being washed to be injured and the washing chamber may be readily flushed out and cleansed after each time it is used.

Other objects and advantages will become apparent from the following detailed description

made in connection with the accompanying drawing, in which

Figure 1 illustrates an elevational view partly in section and with parts broken away of a washing machine constructed in accordance with the 5 present invention;

Fig. 2 is a top plan view partially in section and with parts broken away of the washing machine illustrated in Fig. 1;

Fig. 3 is a sectional view on the line 3—3 of 10 Fig. 1 showing the agitating mechanism of the machine;

Fig. 4 is a fragmentary sectional view on the line 4—4 of Fig. 1, illustrating the agitator and actuating mechanism of the washer; and 15

Fig. 5 is a fragmentary detail illustrating the manner in which the agitating diaphragm is secured to the bottom of the washing chamber.

The various parts of the washing machine illustrated have been indicated by numerals of 20 reference which identify like parts throughout the several views. A substantially cylindrical receptacle 1 which may be formed of any suitable material such as galvanized iron, copper, aluminum, or alloys thereof, defines a washing chamber 25 2. The receptacle 1 is telescopically received by a base 3 which may be in the form of a sheet metal skirt if desired. The base 3 is flared slightly toward the bottom to increase the stability of the machine. Desirably, the telescopic joint between the receptacle 1 and base 3 is brazed or soldered to give a firm connection between the upper and lower parts of the washing machine.

The skirtlike base 3 is carried on a standard 4 which is provided with a plurality of swiveling 35 casters 5 so that the machine may be readily moved. A convenient method of securing the base to the standard is by forming a peripheral flange 6 on the standard 4. This flange engages a circumferential shoulder 7 formed adjacent the 40 lower margin of the base 3. This connection may likewise be secured by brazing or soldering. As shown in Fig. 3, the standard 4 which may satisfactorily be formed of a metal plate, is provided with one or more relatively large openings 8 so 45 that access may be had to the interior of the skirted base 3 in assembling the machine and subsequently in the servicing thereof.

The bottom portions of the side walls of the cylindrical receptacle 1 are formed into an inwardly extending circumferential flange 9. This flange carries a circular deformable and elastic diaphragm 10. The diaphragm thus forms the bottom wall portion of the washing chamber 2. Accordingly, it is desirable that the joint between 50

the flange 9 and marginal portions of the diaphragm 10 be liquid tight.

A suitable manner of forming this connection is illustrated in Fig. 5. The inner edge of the flange 9 is formed into a circumferentially extending collar 11 which engages the under side of the diaphragm 10. A clamping ring member 12 is superimposed upon the upper side of the marginal portion of the diaphragm 10 so that this marginal portion of the diaphragm is held tightly between the ring 12 and flange 9. A plurality of holding screws 14 have their heads engaged by the clamping ring 12 and pass through the diaphragm 10 and circular flange 9. The screws 15 are secured by a number of cap nuts 15 which may desirably be brazed or welded to the bottom of the flange 9. As illustrated in Fig. 5, the clamping ring 12 is not of as great a width as the flange 9, so that the upper surface of the diaphragm 10 extends above the level of the ring 12 and is held in this elevated position by the upstanding collar 11. This method of construction enables the washing liquid to be completely drained from the washing chamber and at the same time affords an effective liquid-tight seal between the flange 9 and diaphragm 10. A suitable spigot 16 is welded into an aperture adjacent the bottom of the receptacle 1 so that washing liquid may be readily drawn off from the washing chamber 2.

A fitting is secured to the central portion of the diaphragm 10 and comprises an upper disk element 17 and a lower disk element 18 which are positioned on opposite sides of the diaphragm 35 and clamped together to secure the diaphragm by means of a bolt 19. The lower disk element 18 carries a wrist pin 21 which secures one end of a reciprocable member or connecting rod 22. The opposite end of the member or connecting rod 22 is carried on a rotating crank arm 23 which is actuated by an electric motor 24 through a worm 25 rotated by the motor shaft and a gear 26 secured to the same shaft as the crank arm 23. The worm 25 and gear 26 are enclosed in a housing 27 which provides journals for the shaft carrying the crank arm 23 and gear 26, as well as journals for the shaft carrying the worm 25. Both the electric motor 24 and the housing 27 are suitably secured to and supported by the standard 4, and the previously mentioned openings 8 permit access to the working parts of the machine so that the actuating mechanism can be properly adjusted and serviced.

The power line for supplying electric current to the motor 24 passes through a suitable rubber grommet 28 held in the base 3 and an electric switch 29 is carried by an upper portion of the base 3 and operable from the exterior thereof so that the washing machine may be started and stopped as desired. The reciprocable connecting rod 22 is arranged with respect to the diaphragm 10 and rotatable crank arm 23 so that the diaphragm 10 is substantially flat or level when the crank arm is horizontal, that is to say, in this position of the crank arm the central portion of the diaphragm to which is secured the upper and lower disk elements 17 and 18 is substantially on a level with the marginal portions thereof which are secured between the clamping 65 ring 12 and flange 9. Accordingly, when the crank arm 23 is rotated into its uppermost position by the worm 25 and gear 26 the central portion of the diaphragm 10 will be raised considerably above the level of the marginal portions thereof. This raising effecting a stretching or

distension of the diaphragm as continued rotation of the gear 26 carries the crank arm 23 to its lowermost position, the diaphragm 10 is lowered so that the central portion thereof is considerably below the marginal portions. At each upward movement the diaphragm contracts slightly until it is substantially level, then stretches or expands until the reciprocable member reaches the top of its stroke. At each downward movement the diaphragm likewise contracts or shrinks and then expands or stretches. Accordingly, each stroke of the reciprocable member 22 causes a contraction and an expansion of the diaphragm and each washing cycle of the machine, generated by a single rotation of the crank 23, causes a double contraction and expansion of the diaphragm.

During operation of the washing machine this up-and-down movement of the central portion of the diaphragm 10 or bottom wall portion of the washing chamber, caused by the reciprocation of the connecting rod 22, agitates the washing liquid A within the cylindrical receptacle 1 and imparts a churning motion thereto. In securing the diaphragm 10 in the bottom of the receptacle 1 it is preferred that the marginal portions of the diaphragm be drawn away from the central portion in order to place the diaphragm under tension. Accordingly, it is proposed to construct the diaphragm 10 out of an elastic material such as rubber, so that it may yield sufficiently to permit the diaphragm to alternately assume the upper and lower positions indicated by the full and broken lines respectively of Fig. 4.

Since the entire weight of the washing liquid in the washing chamber 2 is supported by the diaphragm 10, it is desirable to provide a supporting member 30 to reinforce the diaphragm. This supporting member is preferably in the form of a substantially circular disk having a convex upper surface. A central aperture in the supporting member receives the bolt 19, and the member is thus carried between the upper and lower disk elements 17 and 18 and positioned next 45 adjacent the lower surface of the diaphragm 10. To counterbalance the weight of the washing liquid, a pair of tension springs 31 are arranged to normally urge the diaphragm 10 upwardly. A suitable method of connecting these springs is 50 indicated in Fig. 1, which shows one end of each spring secured to the reciprocable connecting rod 22 adjacent the crank arm 23 and the opposite end of each spring secured to an upper portion of the base 3.

It is to be understood that a washing machine may be constructed in accordance with the present invention without using a reinforcing plate or counterbalancing springs. These are merely refinements of construction which improve the 60 general operating characteristics and facilitate the manufacture of a machine which is commercially more acceptable.

A short distance above the flange 9 the cylindrical receptacle 1 increases slightly in diameter 65 to provide a circumferential shoulder 32. This shoulder carries an article support 33 which is satisfactorily formed by a circular plate or disk having a plurality of apertures 34. During the operation of the washing machine the up and 70 down movement of the diaphragm 10 forces the washing liquid back and forth through the apertures 34 in alternate directions so that the washing liquid is thus forced through and around the articles being washed. At the same time the 75

support 33 serves to retain the articles in spaced relation with respect to the reciprocating diaphragm and the washing operation is performed solely by the liquid being forced over and through the articles without any moving part of the washing machine contacting them.

Articles which tend to rise above the surface of the washing liquid in the chamber 2 are retained in a submerged condition so that they may be effectively washed by the churning liquid by means of a top or hold-down member 35. This article hold-down may be in the form of a circular plate or disk provided with a plurality of apertures 36. A short distance above the shoulder 32 the receptacle 1 again increases in diameter slightly to provide a second shoulder 37. The article hold-down 35 is preferably made with a diameter sufficiently larger than that of the article support 33 so that the hold-down will rest on the shoulder 37 in spaced relation with respect to the article support 33. This construction facilitates removing the article hold-down by inserting one's finger through an aperture 36 without interference therewith by the article support 33. However, the washer will operate satisfactorily without the use of a hold-down plate and this feature is added merely to improve its washing action on certain articles. A suitable cover 38 provided with a handle 39 seats snugly within the top portion of the receptacle 1 to prevent the washing liquid splashing from the chamber 2 during a washing operation.

During the operation of a washing machine constructed in accordance with the present invention the up-and-down movement or reciprocation of the diaphragm 10 is sufficiently rapid so that the washing liquid in the chamber 2 is agitated or churned in contradistinction to a mere flow or movement. Consequently, there will be a positive washing action on the articles positioned in the chamber so that they are quickly and efficiently cleansed. Furthermore, it is clear that the direct and positive connection between the actuating crank 23 and the diaphragm 10 gives a definite and positive movement to the diaphragm which promotes a better movement of the washing liquid.

It is to be noted also that the upper end of the connecting rod or reciprocable member 22 is supported against lateral movements solely by the diaphragm 10. This is accomplished by having the normal position of the diaphragm 10 lying in a plane across the bottom of the receptacle 1 so that there is no opportunity for lateral movement of the disk elements 17 and 18. At no time is there any slack in the diaphragm 10.

It is to be understood that the washing machine shown in the drawing has been presented for purposes of illustration and description only and various modifications and alterations in construction and design are contemplated and intended to be included within the scope of the appended claims.

What we claim is:

1. In a washing machine, a washing chamber for containing a washing liquid, the bottom of said chamber comprising an elastic, deformable diaphragm, said diaphragm normally assuming a substantially flat plane position, a reciprocable member rigidly secured to a central portion of the diaphragm and arranged to alternately stretch and deform the diaphragm upwardly and downwardly to raise and lower the washing liquid in the chamber and cause an agitated and turbulent movement thereof, said reciprocable member

including a disc-like supporting element secured solely at the center thereof to the diaphragm and arranged to underlie a substantial portion of the diaphragm and reinforce the diaphragm against the weight of the washing liquid, the supporting element having a diameter at least substantially half that of the diaphragm, and means for reciprocating the member.

2. In a washing machine, a washing chamber for containing a washing liquid, the bottom of said chamber comprising an elastic, deformable diaphragm, said diaphragm constituting a major portion of area of said bottom and normally assuming a substantially flat plane position, a reciprocable member rigidly secured to a central portion of the diaphragm and arranged to alternately stretch and deform the diaphragm upwardly and downwardly to raise and lower the washing liquid in the chamber and cause an agitated and turbulent movement thereof, driving means for reciprocating said member, and elastic means arranged to counterbalance the weight of the washing liquid sustained by the diaphragm to assist the driving means in raising the liquid.

3. In a washing machine, a washing chamber for containing a washing liquid, the bottom of said chamber comprising an elastic, deformable diaphragm, said diaphragm constituting a major portion of area of said bottom and normally assuming a substantially flat plane position, a reciprocable member rigidly secured to a central portion of the diaphragm and arranged to alternately stretch and deform the diaphragm upwardly and downwardly to raise and lower the washing liquid in the chamber and cause an agitated and turbulent movement thereof, driving means for reciprocating said member, and elastic means arranged to counterbalance the weight of the washing liquid sustained by the diaphragm to assist the driving means in raising the liquid, said elastic means including a spring secured to the reciprocable member and normally urging said member upwardly.

4. In a washing machine, a washing chamber for containing washing liquid, an elastic diaphragm forming a wall portion of the chamber and normally assuming a substantially flat plane position, a reciprocable member rigidly secured to a relatively small central part of the diaphragm, driving means to reciprocate said member to alternately stretch the diaphragm substantially into the form of a cone and move to permit the diaphragm to contract by inherent resiliency to the substantially flat plane position, whereby washing liquid in the chamber is agitated, and elastic means on the opposite side of the diaphragm from the washing liquid and arranged to counterbalance the pressure of the washing liquid against the diaphragm.

5. In a washing machine, a washing chamber for containing a washing liquid, an elastic diaphragm forming a wall portion of the chamber and normally assuming a substantially flat plane position, a reciprocable member rigidly secured to a relatively small central part of the diaphragm, driving means to reciprocate said member to alternately stretch the diaphragm substantially into the form of a cone and move to permit the diaphragm to contract by inherent resiliency to the substantially flat plane position, whereby washing liquid in the chamber is agitated, and a plate positioned against the diaphragm on the opposite side thereof from the washing liquid, said plate being secured to the

- reciprocable member and arranged to reinforce the diaphragm against the pressure of the washing liquid, the plate having a width at least substantially half that of the diaphragm.
5. 6. In a washing machine, a washing chamber for containing a washing liquid, an elastic diaphragm forming a wall portion of the chamber and normally assuming a substantially flat plane position, a reciprocable member rigidly secured 10 to a relatively small central part of the diaphragm, driving means to reciprocate said member to alternately stretch the diaphragm substantially into the form of a cone and move to permit the diaphragm to contract by inherent resiliency 15 to the substantially flat plane position, whereby washing liquid in the chamber is agitated, and a plate carried by the reciprocable member positioned against the diaphragm on the opposite side thereof from the washing liquid, the plate having a width at least substantially half that of 20 the diaphragm and arranged to reinforce the diaphragm against the pressure of the washing liquid.
7. In a washing machine, a washing chamber 25 for containing a washing liquid, an elastic diaphragm forming a wall portion of the chamber and normally assuming a substantially flat plane position, a reciprocable member rigidly secured to a relatively small central part of the diaphragm, driving means to reciprocate said member to alternately stretch the diaphragm substantially into the form of a cone and move to permit the diaphragm to contract by inherent resiliency to the substantially flat plane position, 30 whereby washing liquid in the chamber is agitated, a plate and elastic means connected to the reciprocable member and positioned on the opposite side of the diaphragm from the washing liquid, the plate having a width at least substantially half that of the diaphragm and arranged to reinforce the diaphragm against the pressure of the liquid and the elastic means being arranged to counterbalance the pressure of the liquid against the diaphragm.
- 35 8. In a washing machine, a washing chamber for containing a washing liquid, an elastic diaphragm forming a wall portion of the chamber and normally assuming a substantially flat plane position, a reciprocable member rigidly secured 40 to a relatively small central part of the diaphragm, driving means to reciprocate said member to alternately stretch the diaphragm substantially into the form of a cone and move
- to permit the diaphragm to contract by inherent resiliency to the substantially flat plane position, whereby washing liquid in the chamber is agitated, and elastic means on the opposite side of the diaphragm from the washing liquid and arranged to counterbalance the pressure of the washing liquid, said elastic means comprising a spring connected to the reciprocable member and normally urging the member toward the washing liquid.
9. In a washing machine, a washing chamber 10 for containing a washing liquid, said chamber having substantially vertical walls and a bottom comprising a deformable diaphragm arranged to be alternately displaced in opposite directions to agitate washing liquid in the chamber, an annular flange member on the vertical walls of the chamber, an annular ring member, the peripheral edges of the diaphragm being clasped between said annular ring member and the annular flange member on the chamber walls, an outlet spigot in communication with the bottom-most part of the chamber for draining washing liquid therefrom, and the annular member beneath the diaphragm being formed to retain the top surface of the portions of the diaphragm supported thereby above the top surface of the other annular member to substantially prevent entrapment of washing liquid in the chamber by the uppermost annular member when draining through the 20 spigot.
10. In a washing machine, a substantially cylindrical receptacle defining a washing chamber for containing a washing liquid, said receptacle having portions of decreased diameter 35 toward the bottom of the chamber to provide axially spaced shoulders, a pair of non-buoyant perforated partitions receivable in the chamber, one of said partitions resting by gravity on one of said shoulders adjacent the bottom of the 40 chamber and the other partition axially movable through the major portion of the chamber, the lower limit of movement of said last named partition being established by another of said shoulders and when in said lower limit of movement said partition being in spaced parallel relation with respect to the first named partition, said last named partition normally resting by gravity on the top of articles being washed and beneath the surface of the washing liquid.
